ABSTRACT

An inner contact of a coaxial connector has a body with a plurality of spring fingers, the spring fingers each provided with a contact surface. A plurality of transitions from the contact surfaces are provided as curved surfaces. The curved surfaces may be formed, for example, by chamfer, electrical discharge machining or the like, such that an edge to a slot between the spring fingers does not contact the contact surface.

CURVED TRANSITION SURFACE INNER
CONTACT

BACKGROUND

1. Field of the Invention

This invention relates to electrical cable connectors. More particularly, the invention relates to an inner contact for a coaxial connector with improved passive intermodulation distortion (PIM) electrical performance and mechanical interconnection characteristics.

2. Description of Related Art

Coaxial cable connectors are used, for example, in communication systems requiring a high level of precision and reliability.

To create a secure electro-mechanical interconnection between the cable and the connector, it is desirable to have generally uniform, circumferential contact between the conductors of the coaxial cable and the coaxial connector. Interconnection with the inner conductor may be provided by an inner contact utilizing a plurality of spring fingers to securely engage the inner conductor. Representative of this technology is commonly owned U.S. Pat. No. 7,803,018, titled "Inner Conductor End Contacting Coaxial Connector and Inner Conductor Adapter Kit" issued 28 Sep. 2010 to Nahid Islam.

During systems installation, axial and/or rotational forces may be applied to the connector, for example as the inner conductor is inserted into engagement with the inner contact and the attached coaxial cable is routed towards the next interconnection and maneuvered into position and/or curved for alignment with cable supports and/or retaining hangers. Rotation of the coaxial cable and coaxial connector with respect to each other may damage the connector, the cable and/or the integrity of the cable/connector inter-connection. Further, once installed, twisting, bending and/or vibration applied to the interconnection over time may degrade the connector to cable interconnection and/or introduce PIM.

Competition in the coaxial cable connector market has focused attention on improving electrical performance and minimization of overall costs, including materials costs, and training requirements for installation personnel.

Therefore, it is an object of the invention to provide an inner contact for a coaxial connector that overcomes deficiencies in the prior art.

BRIEF DESCRIPTION OF THE DRAWINGS

The accompanying drawings, which are incorporated in and constitute a part of this specification, illustrate embodiments of the invention, where like reference numbers in the drawing figures refer to the same feature or element and may not be described in detail for every drawing figure in which they appear and, together with a general description of the invention given above, and the detailed description of the embodiments given below, serve to explain the principles of the invention.

FIG. 1 is a schematic isometric view of an exemplary inner contact engaged with an inner conductor.

FIG. 2 is a schematic isometric cut-away view of the assembly of FIG. 1.

FIG. 3 is a schematic end view of the assembly of FIG. 1.

FIG. 4 is a schematic isometric view of a body, prior to initiating processing into an inner contact.

FIG. 5 is a schematic isometric cut-away view of the body of FIG. 4.

FIG. 6 is a schematic isometric view of the body of FIG. 4, after chamfering.

2

FIG. 7 is a schematic isometric cut-away view of the body of FIG. 6.

FIG. 8 is a schematic end view of the body of FIG. 6.

FIG. 9 is a schematic isometric view of the body of FIG. 6, after slotting.

FIG. 10 is a schematic isometric cut-away view of the body of FIG. 9.

FIG. 11 is a schematic end view of the body of FIG. 9.

FIG. 12 is a schematic isometric view of the body of FIG. 9, after swaging.

FIG. 13 is a schematic isometric cut-away view of the body of FIG. 12.

FIG. 14 is a schematic end view of the body of FIG. 12.

FIG. 15 is a schematic isometric view of an alternative embodiment of an inner contact for hollow inner conductors.

FIG. 16 is a schematic end view of the inner contact of FIG. 15.

DETAILED DESCRIPTION

The inventors have recognized that initial insertion, movement and/or skewing of alignment between the inner contact of a coaxial connector and the inner conductor of a coaxial cable may scrape and/or scratch the surface of the inner conductor, generating PIM.

The scraping and/or scratching is believed to result in part from the sharp edges at the sides of the spring finger contact areas generated by conventional methods of forming the spring fingers of the inner contact, such as machining by sawing or the like across the end of the inner contact to form the spring fingers, leaving sharp edges therebetween. The scraping and/or burrs remaining along the sharp edges may also generate metal chips that can then migrate within the interconnection area, creating a further source of PIM.

As shown for example in FIGS. 1-3, an exemplary inner contact 1 of a coaxial connector has a body 3 with a plurality of spring fingers 5 formed from a portion of the body 3 surrounding an inner conductor bore 7 open to a cable end of the inner contact 1. The spring fingers 5 are each provided with a contact surface 9 positioned, for example, proximate a distal end of the spring fingers 5, the contact surfaces 9 dimensioned to contact the inner conductor 11 of a coaxial cable interconnected with the coaxial connector.

Transitions 13 from the periphery of the contact surfaces 9 to the remainder of the spring finger 5 may be provided as curved surfaces. The curved surfaces may be formed including a radius, chamfer, relief and the like. Thereby the periphery of the contact surfaces 5 may be provided without sharp edges or burrs.

The inner contact 1 with spring fingers 5 and curved surface transitions 13 may be cost efficiently manufactured, for example, by forming the curved surface transitions 13 upon a body 3 provided with an inner conductor bore 7 at the cable end, for example as shown in FIGS. 4 and 5. An inward projecting annular projection 15 may be provided proximate a distal end of the inner conductor bore 7 for further processing into the desired contact surfaces 9 and curved surface transitions 13. The curved surfaces may be applied, for example by broaching or electrical discharge machining, to obtain a curved surface without introducing sharp edges at the periphery of the contact surfaces 9 where the machining removes material.

After the curved surface transitions have been machined, for example as shown in FIGS. 6-8, slots defining the spring fingers 5 may be applied, for example by conventional machining such as sawing or the like, between the transitions 13, for example as shown in FIGS. 9-11. Alternatively, the

order of operation may be reversed by machining the slots and then applying the curved surface of the transitions **13** to the edges between the slots and the contact surfaces **9**.

Because an edge between the transitions **13** and the slots is spaced away from the contact surfaces **9**, any sharp edge or burr generated at the intersection of the slot and the transition **13** by the use of conventional sawing or the like will not contact the inner conductor **11**.

A swaging operation may be applied, for example radially inward proximate the distal end of the spring fingers **5**, to increase a bias of the spring fingers **5** upon the inner conductor **11**, for example as shown in FIGS. 12-14.

One skilled in the art will appreciate that inner contacts **1** with curved surface transitions **13** may be configured to engage the outer diameter of an inner conductor **11** by applying the contact surfaces **9** to an inner surface **17** of the spring fingers **5**, or alternatively the inner diameter of a hollow inner conductor by applying the contact surfaces **9** to an outer surface **19** of the spring fingers **5**. In outer diameter contact surface configurations, for example as shown in FIGS. 15 and 16, the outward projecting annular projection **15** may be provided on an outer diameter of the distal end of the inner contact **1**.

One skilled in the art will appreciate that contact surfaces of inner contacts with periphery transitions applied as curved surfaces may decrease PIM generation and thereby improve interconnection electrical performance. Further, because scratching of the inner conductor is less likely even if the installation steps are performed roughly, installation may be successfully performed by personnel with lower training requirements.

Table of Parts

5	17	inner surface
	19	outer surface

Where in the foregoing description reference has been made to materials, ratios, integers or components having known equivalents then such equivalents are herein incorporated as if individually set forth.

While the present invention has been illustrated by the description of the embodiments thereof, and while the embodiments have been described in considerable detail, it is not the intention of the applicant to restrict or in any way limit the scope of the appended claims to such detail. Additional advantages and modifications will readily appear to those skilled in the art. Therefore, the invention in its broader aspects is not limited to the specific details, representative apparatus, methods, and illustrative examples shown and described. Accordingly, departures may be made from such details without departure from the spirit or scope of applicant's general inventive concept. Further, it is to be appreciated that improvements and/or modifications may be made thereto without departing from the scope or spirit of the present invention as defined by the following claims.

We claim:

1. An inner contact of a coaxial connector, comprising: a body with a plurality of spring fingers, the spring fingers each provided with a contact surface; a plurality of transitions between a periphery of each of the contact surfaces and their respective spring fingers, including transitions proximate adjacent spring fingers, provided as curved surfaces; wherein the contact surface is on an outer surface of the spring fingers.
2. The inner contact of claim 1, wherein the curved surface is a radius.
3. The inner contact of claim 1, wherein the curved surface is a chamfer.
4. The inner contact of claim 1, wherein the curved surface is a relief.
5. The inner contact of claim 1, wherein the contact surfaces are provided proximate a distal end of the spring fingers.
